COMBINATION TRAILER AND WIRE STRINGER

Gerald A. M. Petersen, Santa Clara, Calif.

Application May 3, 1956, Serial No. 41,323

Term of patent 14 years

(Cl. D14—3)

Fig. 1 is a plan view of a combination trailer and wire stringer embodying my new design.

Fig. 2 is a side view of Fig. 1; and

Fig. 3 is a perspective view.

The characteristic features of my design reside in the centrally disposed drum mounting as shown.

I claim:

The ornamental design for a combination trailer and wire stringer, as shown and described.
